(57) **CLAIM**

The ornamental design of a vacuum cleaner tool door, as shown and described.

DESCRIPTION

FIG. 1 is a perspective view of a vacuum cleaner tool door showing the tool door positioned on a canister vacuum cleaner which is shown in dashed lines;

FIG. 2 is a perspective view of the tool door of FIG. 1;

FIG. 3 is a right side elevational view thereof;

FIG. 4 is a top plan view thereof;

FIG. 5 is a front elevational view thereof; and,

FIG. 6 is a rear elevational view thereof.

The left side elevational view being a mirror image of the right side elevational view of FIG. 3, and the dashed lines in FIG. 1 being for the purpose of environment only.
